UNITED STATES PATENT OFFICE.

GEORGE B. KELLEY, OF ROCKFORD, ILLINOIS, ASSIGNOR TO THE ROCKFORD SILVER PLATE COMPANY, OF SAME PLACE.

DESIGN FOR A SPOON OR FORK HANDLE.

SPECIFICATION forming part of Design No. 14,911, dated March 25, 1884.

Application filed February 18, 1884. Term of patent 7 years.

To all whom it may concern:

Be it known that I, GEO. B. KELLEY, of Rockford, in the county of Winnebago and State of Illinois, have invented a new Design 5 for Spoon and Fork Handle; and I do hereby declare the following, when taken in connection with accompanying drawing and the letters of reference marked thereon, to be a full, clear, and exact description of the same, 10 and which said drawing constitutes part of this specification, and represents a face view.

This design relates to the handles of spoons, forks, and like articles of table-service; and it consists in the configuration and ornamentation, as shown in the accompanying illustration, 15 and hereinafter described.

The handle, from its connection with the bowl, expands slightly to the boss midway of the length of the handle. The boss is of lozenge 20 shape, one angle projecting from each side. From this boss the sides of the handle converge to the end. At the end the line of the sides turns inward by about a quarter-circle, and from these segments a line inclines upward 25 to a central point. The bead around the edge forms a panel upon the surface. Diagonally across this panel, extending from border to border, is a band composed of two beads, with a vine between them. On the surface

below the band a vine is represented as springing from the boss, but dying out behind the band. At the tip end, on the surface of the panel, a segment-shaped bead extends from side to side, the curve upward, and between the bead and the border, at the tip, is the representation of floriated tracery, all as shown in the accompanying illustration.

I claim—

The herein-described design for spoon and fork handle, consisting of the lozenge-shaped 40 boss midway of the length of the handle, from the boss the line of the sides of the handle converging to the end, there curved over and inward, thence inclined upward to the center, the edge of the handle having the bead following its outline and forming a panel upon the surface, on the said panel a diagonal band extending from the border at one side to the border upon the opposite side, a segment-shaped bead across the panel near the tip, the 45 space between the bead and the tip ornamented with the representation of floriated tracery, as shown in the accompanying illustration.

GEORGE B. KELLEY.
